UNITED STATES PATENT OFFICE.

JAMES H. SMITH, OF SOUTH WEYMOUTH, MASSACHUSETTS.

OIL BURNER.

Application filed March 1, 1926. Serial No. 91,327.

This invention relates to oil burners and particularly to the part thereof by which the oil vapor is mixed with the air to produce the combustible mixture.

5 Some objects of the invention are to provide an oil burner having a novel form of mixing chamber which is simple in construction but by which a more perfect mixture can be obtained, and to provide a novel 10 construction by which the cleaning of the vaporizing tube may be facilitated.

In order to give an understanding of the 15 invention I have illustrated in the drawings a selected embodiment thereof which will now be described after which the novel features will be pointed out in the appended 20 claims.

Fig. 1 is a sectional view of an oil burner embodying my invention and adapted to be 25 used in a kitchen range;

Fig. 2 is a top plan view of the burner;

Fig. 3 is an enlarged sectional view of the 30 mixing chamber;

Fig. 4 is a fragmentary view of one end 35 of the burner showing the opening through the head 3 through which the vaporizing tube is introduced or withdrawn, the vaporizing tube being shown in section.

The burner herein illustrated is of that 40 familiar type which comprises a plurality of burner elements 1 in the form of burner tubes which are connected to two end members 3 and 4, each burner tube having burner openings 2 therein. The burner tubes and 45 end members are tied together by means of tie rods 5 this being the usual construction.

In the case of a device adapted to be used 50 in the fire-box of a kitchen range the length of the burner tubes and the size of the end 55 pieces 1 will be such as to permit it to be set into said fire-box as shown in Fig. 1, wherein 60 indicates generally a kitchen range having the usual grates 7 and the fire-box 8 above the grates. Burners which are adapted 65 for kitchen range use are usually supported on the grate as shown in Fig. 1.

The end piece 4 of the burner herein 70 shown is in the nature of a header into which the combustible mixture of oil vapor 75 and air is introduced, the interior of the

header communicating with the burner tubes 1 so that the combustible mixture which is delivered to the header will pass into the burner tubes.

9 indicates a vaporizing tube which is 55 connected to the oil supply and in which the oil is vaporized. This tube is situated above one of the burner tubes so as to be heated thereby, as usual in devices of this character and it has connected to its end a 60 supply pipe 10 leading to a source of oil supply. The delivery end of the vaporizing tube is shown as secured to a head 11 which is provided with a small delivery orifice 12 through which the oil vapor is delivered 65 with more or less force. This oil vapor is delivered into a mixing chamber with which one feature of my present invention is concerned.

This mixing chamber is in the form of a 70 tube 13 which is open at both ends, one end of said tube being screwed into the wall of the header 4 and the other end of said tube being situated adjacent the delivery orifice 12. The end 14 of the mixing tube adjacent 75 the orifice 12 is of smaller diameter than the end 15 which communicates with the header 4 and said tube is provided with one or more air inlet openings 16 that lead into the enlarged end 15 adjacent the point where it 80 connects with the smaller end 14. The outer end of the smaller portion 14 is preferably provided with a flared mouth 17 to facilitate the entrance of air.

The head 11 and its vaporizing tube can 85 be adjusted toward and from the mixing tube and when the head 11 is properly adjusted and the burner is operating the stream or jet of vaporized oil will be delivered from the aperture 12 with considerable 90 force and under pressure and will be directed into the smaller end 14 of the mixing chamber. This stream of vaporized oil will produce a suction which will draw air into the smaller end 14 of the mixing tube, 95 such air becoming mixed with the oil vapor. The oil vapor which is delivered to the mixing tube will expand more or less in the smaller portion 14 but will be delivered into the enlarged portion 15 with more or less 100

pressure. As the mixture enters the enlarged portion 15 it will expand again and will also produce suction through the inlet ports 16 which will draw in an added supply 5 of air, this added air becoming mixed with the charge which is delivered from the smaller portion 14. With this arrangement there is a double or two-stage expansion, one stage occurring in the smaller portion 14 of 10 the tube and the other in the large portion 15.

I find that with this arrangement and with this two-stage expansion and with the construction by which the air is also admitted 15 into the mixing chamber at two different places a more complete mixture of the oil vapor and air is secured and the flame will burn at the burner openings 2 with little or no carbonization.

20 Another feature of my invention relates to the adjustability of the vaporizing tube 9. This vaporizing tube rests freely on supports 18 and can be adjusted longitudinally on said supports so as to vary the distance 25 of the delivery orifice 12 from the end of the mixing tube. This vaporizing tube is further arranged so that it can be readily removed from the burner.

In the operation of an oil burner of this 30 type the part which requires most attention so far as cleaning is concerned is the vaporizing tube. In order that the burner should operate correctly it is, of course, necessary that the delivery orifice 12 should always 35 be free and it is desirable also to occasionally clean out the interior of the vaporizing tube.

In the present construction this vaporizing tube with its head 11 is readily removable from the burner to facilitate the cleaning 40 operation as well as being adjustable relative to the mixing chamber 13.

For adjusting the vaporizing tube I have 45 provided the following mechanism. The end of the tube is provided with a groove 19 in which is received one side of the head of an adjusting screw 20 which screws into a head 3. By turning the adjusting screw one way or the other the vaporizing tube which rests freely on its support 18 will 50 be adjusted longitudinally thereby to vary the distance of the delivery orifice 12 from the end of the vaporizing tube. By means of this construction it is possible to adjust the vaporizing tube so that it will operate in 55 the most efficient manner under the conditions of use.

The end 3 is provided with an opening 21 through which the vaporizing tube extends and this opening is large enough to permit 60 the head 11 to be passed therethrough. The bottom of the opening is formed with a slight recess or depression 22 in which the vaporizing tube is received and which prevents lateral movement of the vaporizing tube when it is adjusted by the screw 20.

To remove the vaporizing tube it is necessary first to disconnect the supply pipe 10 therefrom and when this has been done said vaporizing tube may be withdrawn from the burner through the aperture 21 and when 70 withdrawn it may be readily cleaned.

In some kitchen ranges the end 23 of the stove is in the form of a door which may be opened to facilitate the withdrawal of the vaporizing tube from the burner. Where 75 said end 23 is not in the form of a door it may be provided with an opening 24 of sufficient size to permit the withdrawal of the vaporizing tube therethrough. With 80 this construction the operation of removing the vaporizing tube for cleaning purposes or for the purpose of substituting another tube is a relatively simple operation.

While the burner elements 1 are herein shown as burner tubes yet I wish to state 85 that these burner elements may be in some other form than burner tubes without departing from the invention. Furthermore, although I have illustrated herein a selected embodiment of the invention yet it will be understood that various changes in the constructional details may be made without departing from the invention.

I claim:

1. In an oil burner, the combination with 95 a plurality of burner tubes, of two end members to which the ends of the tubes are secured, one of said members being in the form of a manifold with which the burner tubes communicate and the other member 100 having an opening therethrough, a tubular mixing chamber communicating at one end with the manifold member and open at the other end, a loosely-supported vaporizing tube in which the oil is vaporized, a discharge head rigid with the vaporizing tube 105 at one end thereof and spaced slightly from the open end of the mixing chamber, said head having a discharge orifice to deliver a jet of vaporized oil into the open end of 110 the mixing chamber, the other end of said vaporizing tube extending through the opening in the end member, which opening is of sufficient size to permit the discharge head 115 to pass therethrough, said vaporizing tube and discharge head being separable from the other parts of the burner, whereby the vaporizing tube and discharge head may be readily removed from the burner by withdrawing them through said opening.

2. In an oil burner, the combination with 120 two end members, one of which has an opening therethrough, of a plurality of burner tubes connecting said members, the other member constituting a manifold with which the burner tubes communicate, a tubular mixing chamber communicating at one end with the manifold and open at the other end, a vaporizing tube having a discharge head 125 at one end provided with a discharge orifice, 130

said tube being detachable from the burner and being loosely supported in position with the discharge orifice directed toward the open end of the mixing chamber, and means for adjusting the vaporizing tube in the direction of its length, said opening through the end member being of a size to permit the discharge head to pass therethrough and the

vaporizing tube being separable from its adjusting means, whereby said vaporizing tube and discharge head may be readily removed from the burner.

In testimony whereof, I have signed my name to this specification.

JAMES H. SMITH.
